UNITED STATES PATENT OFFICE.

CHARLES ADIS PURVIS AND THOMAS ANDREW PURVIS, OF ST. JOSEPH, MISSOURI.

MOP.

Application filed November 2, 1926. Serial No. 145,814.

This invention relates to mops and more particularly to the provision of a general purpose mop.

An important object of the invention is 5 to provide a construction of this character such that the mopping element may be held very evenly and firmly against the surface being mopped and may be held in such position that it may be readily inserted into corners beneath radiators or between the sections thereof.

A further object of the invention is to provide a construction of this character such that the mopping element may be readily removed and replaced, so that by the provision of a proper number of mopping elements, it may be employed in any mopping operation.

A still further object of the invention is to 20 provide a device of this character which may be readily and cheaply produced, which may be durable and efficient in service and a general improvement in the art.

These and other objects we attain by the 25 construction shown in the accompanying drawing, wherein for the purpose of illustration is shown a preferred embodiment of our invention and wherein:—

Figure 1 is a front elevation partially 30 broken away of a mop constructed in accordance with our invention;

Figure 2 is a vertical sectional view therethrough;

Figure 3 is a section at right angles to that 35 taken in Figure 2;

Figure 4 is a fragmentary side elevation showing the manner in which the mop tensioning element maintains the mop element at the proper engagement with the surface 40 which is being mopped.

Referring now more particularly to the drawing, the numeral 10 indicates a handle of any suitable description having at its lower end a transversely extending head 11. 45 The handle and head are relatively rotatable and the end of the handle has embedded therein a bolt 12 rotatably directed through a bore 13 formed in the head centrally thereof. The lower face of the head is 50 longitudinally arcuately grooved at 14 for the reception of a clamping bar 15, which bar has threaded engagement with the bolt 12 through a nut 16 embedded therein.

Secured to the bar are the ends of arms 55 19 of a U-shaped mop element distending holder 20. This holder is formed from

spring wire and has the cross bar 21 thereof straight and parallel to the bar 15, while the arms 19 are sinuous, so that they provide a relatively broad holding surface for the 60 sides of the mop element M. The bar engaging ends of the arms are provided with inturned extensions 22 having at their free ends angular tangs 23 adapted to enter the bar. Adjacent the connections of the angular extensions with the ends of the arms staples 24 secure the extensions to the bar, while at the same time, permitting rotation of the extensions. While in the present illustration, the extensions are illustrated 65 as overlapping, it will be obvious that these extensions could be shortened, if desired. The mop element is formed of a continuous band of cloth having an opening 25 formed 70 therein for the passage of the bolt 12 and is of such length that when applied to the bar and the mop distending element, the side faces of the cloth are stretched.

It will be obvious that the sinuous construction of the arm will permit these arms 80 to readily flex, so that they will conform to the surface with which the mop is engaged and permit the mop element to flatly engage thereagainst, while the handle is disposed at an angle to the surface, as indicated 85 in Figure 4. The relatively broad surface provided by the arms and the tension applied thereto by the cloth will prevent the cloth from pulling sideways and improperly engaging against the surface. Each of the 90 arms can furthermore yield longitudinally, so that there is no danger of damaging a surface by unevenly engaging the free or cross bar engaged portion of the mopping element therewith unevenly. It will be obvious that since the material employed is 95 resilient and the extensions 22 are relatively long, a twist can occur in these extensions, permitting angular displacement of the arms with relation to the head, while at the same time, the arms are pressed firmly into engagement with the surface being mopped.

Since the construction hereinbefore set forth is capable of a certain range of change and modification without materially departing from the spirit of the invention, we do not limit ourselves to such specific structure except as hereinafter claimed.

We claim:—

1. A mop including a head, a handle, the head having a groove, a bar engageable in said groove, a detachable connection between

the bar and the handle, passing through the head, a cross bar confronting the first bar and connected thereto by members yieldable longitudinally and a mop band passed about the bars and clamped between the first bar and the head.

2. A mop as set forth in claim 1 wherein the members connecting the bar and cross bar are sinuous in the general plane of the 10 aforementioned bars.

3. A mop as set forth in claim 1, wherein the detachable connection between the handle and bar comprises a bolt embedded in the handle and having its free end thread- 15 edly engaging said bar.

4. A mop including a handle, a head car-

ried thereby, a bar, a connection between the bar and handle for clampingly engaging the bar with the head, a cross bar confronting the first bar and connected thereto by 20 members yieldable longitudinally and a mop band passed about the bars and clamped between the first bar and the head.

5. A mop as set forth in claim 4, wherein the members connecting the bar and cross 25 bar are continuations of the cross bar and are sinuous in the general plane of said bars.

In testimony whereof we hereunto affix our signatures.

CHARLES ADIS PURVIS.
THOMAS ANDREW PURVIS.
